UNITED STATES PATENT OFFICE

GROVER LOENING, OF NEW YORK, N. Y.

DESIGN FOR A FLYING BOAT

Application filed June 27, 1930. Serial No. 36,210. Term of patent 14 years.

To all whom it may concern:

Be it known that I, GROVER LOENING, a citizen of the United States, residing at New York city, in the county and State of New York, have invented a new, original, and ornamental Design for Flying Boats, of which the following is a specification, reference being had to the accompanying drawing, forming part thereof.

Fig. 1 is a plan view of a flying-boat, showing my new design;
Fig. 2 is a side elevation; and
Fig. 3 is a front elevation.

I claim:

The ornamental design for a flying-boat, as shown.

GROVER LOENING.
